UNITED STATES PATENT OFFICE.

PAOLO DI BENEDETTO, OF SPRINGFIELD, VERMONT.

LAMP-POST.

1,359,039.

Specification of Letters Patent. Patented Nov. 16, 1920.

Application filed April 2, 1919, Serial No. 286,863. Renewed July 27, 1920. Serial No. 399,442.

To all whom it may concern:

Be it known that I, PAOLO DI BENEDETTO, a subject of the King of Italy, residing at Springfield, in the county of Windsor and 5 State of Vermont, have invented certain new and useful Improvements in Lamp-Posts, of which the following is a specification.

The primary object of the invention is 10 the provision of a lamp serviceable at any elevated point such as a newell post, balcony or the like designed for employing either electricity or oil for supplying the light, the structure having an ornamental 15 external appearance, arrangements being made for the proper care of the illuminating member.

A further object of the invention is to 20 provide an elevated holder for an interchangeable lighting member such as an oil and an electric lamp whereby either of the same may be employed suitable to the requirements of the surrounding conditions, the lamp being accessible when required and 25 the exterior of the invention being normally finished and attractive.

With these general objects in view the invention consists of the combination and arrangement of parts hereinafter fully illustrated in the accompanying drawings and in which like reference characters designate corresponding parts throughout the several view.

In the drawings, 30 Figure 1 is a front elevation of the invention employing an oil lamp for illuminating purposes.

Fig. 2 is a vertical transverse sectional view thereof,

Fig. 3 is a view partially in side elevation and partly in vertical section showing the invention provided with an electric lighting means,

Fig. 4 is a top plan view of the same 45 with the ornamental cap removed,

Fig. 5 is a similar view of a central portion thereof with the electric lamp and its holder removed and

Fig. 6 is a perspective view of the electric 50 lamp holder.

My invention broadly consists of a sheet metal post 10 provided with an ornamental cap 11 preferably in the form of the bust of an individual, such as Shakespeare, as here- 55 in illustrated, provision being made for mounting an illuminating body within the

cap 11 for shedding rays of light through eye-openings 12 and through a central top opening 13 of the cap or bust 11, the latter being preferably formed of frosted glass. 60

The bust 11, has a frusto-conical base 14 seated within a positioning rim 15 marginally provided upon the top 16 of the post 10, it being noted that the top 16 is at the upper end of the tapered upper portion 17 65 of the said post.

A central opening 18 is provided through the top 16 for receiving the oil container 19 of a fluid oil burner or lamp 20. The lamp 20 has the usual form of controlling member 21 while its transparent chimney 22 vertically extends and terminates at the said top opening 13.

It will be understood that the bust 11 may be readily removed from the top 16 when the lamp is positioned thereon so that the lamp 20 is then accessible for refilling, regulating and any other care which may be required, the bust being returned and normally seated within the rim 15 as illustrated. 70 The cap 11 may represent an animal, such as a lion if desired or any individual. 80

When it is desired to employ electricity for lighting purposes, the usual form of electric lamp 22 is provided with its socket 23 seated within an upstanding flange 24 of an accommodator or ring 25 and upon an inwardly projecting flange 26. The ring 25 is seated upon the top 16 of the post 10 with a depending flange 27 of the ring extending through the opening 18 of said top. 85

The lamp 23 being mounted upright in the ring 25 and the ring positioned upon the top 16 as described, the circuit wires 28 extend downwardly through the post 10 and outwardly through a perforation 29 in the post to a suitable source of electrical supply. The lamp socket 23 being of the pull style, has an operating chain 30 by means of which the electric light is turned on and off as desired, the said chain extending downwardly in the post and through a side opening 31 therein to a point that is readily accessible exteriorly of the post for controlling the lamp 22 as found desirable. 90

A side notch 32 is provided in the top 16 of the post communicating with the central opening 18 thereof, with which notch, a side notch 33 of the ring 25 is adapted to register for receiving the pull chain 30 there- 105 through. 110

The bust 11 may be formed of metal so

that the entire structure is fire-proof and the light within the said bust throws a glow in the form of indirect lighting in the immediate vicinity of the post 10. The bust may 5 also be formed of semi-transparent material, such as porcelain or colored glass instead of metal if desired.

My invention is especially serviceable as a 10 night light, where it is unnecessary to clearly discern surrounding objects but a continuing light is advisable as well as one in which the full capacity of the lamp may be easily obtained by removing the cap or bust 11.

What I claim as new is:—

15 1. A device of the class described comprising a tubular metallic post having a tapered upper portion, a top provided for the post having an annular rim and further having a central opening provided with a 20 side notch, an accommodating ring having a side notch corresponding with the notch of said top when the device is assembled, a downwardly projecting flange surrounding the central opening of the ring depending 25 through the opening of the top, an upwardly projecting and an inwardly projecting flange upon the ring adapted for seating a lamp socket therein and a cap in the form of a bust removably positioned upon the 30 top and within said rim provided with a

top and eye-openings through which rays of light are adapted for projection.

2. A device of the class described comprising a tubular metallic post having a tapered upper portion, a top provided for 35 the post having an annular rim and further having a central opening provided with a side notch, an accommodating ring having a side notch corresponding with the notch of said top when the device is assembled, a 40 downwardly projecting flange surrounding the central opening of the ring depending through the opening of the top, an upwardly projecting and an inwardly projecting flange upon the ring adapted for seating a lamp 45 socket therein, the said post having perforations through the side thereof, an electric lamp socket seated upright in said ring, circuit wires and a pull chain for the latter extending through said perforations outwardly of the post and a frosted glass cap having a frusto-conical base seated upon the top of the post within said rim for surrounding the lamp and having eye-perforations and a top opening adapted for the projection 50 of light from the lamp therethrough when the device is assembled.

In testimony whereof I affix my signature.

PAOLO DI BENEDETTO.
